UNITED STATES PATENT OFFICE.

WALTER D. STEELE, OF EVANSTON, AND REUBEN B. BENJAMIN, OF CHICAGO, ILLINOIS, ASSIGNORS TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed December 8, 1919. Serial No. 343,307.

To all whom it may concern:

Be it known that we, WALTER D. STEELE, a citizen of the United States, residing at Evanston, in the county of Cook and State of Illinois, and REUBEN B. BENJAMIN, a citizen of the United States, residing at Chicago, in the county of Cook and State of Illinois, have invented certain new and useful Improvements in Electrical Connecter Devices, of which the following is a full, clear, concise, and exact description, reference being had to the accompanying drawings, forming a part of this specification.

Our invention relates to electrical connecter devices and more specifically to plug receptacles, that is to say, to connecter devices of the type having a plug portion for insertion into a receptacle and having a receptacle portion into which another plug portion can be inserted.

In plug receptacles, as commonly constructed, (and particularly when a plurality of receptacles are provided or when a receptacle is provided with a switch) it will often happen when the plug portion of the device is screwed into the receptacle to make the desired connection, that the receptacle portion of the device will not be in the desired position. The plug portion, of course, is screwed in tight until a good contact is made, and the receptacle portion will then be in whatever position this screwing in of the plug happens to bring it. This may result in making the lamp or other device which is put into the receptacle portion of the device, extend in the wrong direction or it may bring the switch mechanism into an undesirable position which would make it difficult to operate or (in the case of a pull switch) it may bring the pull chain into such a position that the chain would have to be pulled at an awkward angle, which would interfere with the proper operation of the switch mechanism.

One of the objects of our invention is to provide improved means whereby the plug portion of the device may be screwed firmly into a socket, and the outer portion of the device thereafter given a certain amount of adjustment to bring said outer part into the desired position.

Further objects of our invention are to provide a construction which will be du-

rable and efficient in use, simple in construction and cheap to manufacture.

Further objects will appear from the detailed description to follow and the appended claims.

In the drawings—

Fig. 1 is a vertical longitudinal partially sectional view of our device;

Fig. 2 is a sectional view on the line 2—2 of Fig. 1 looking in the direction of the arrows;

Fig. 3 is a sectional view on the line 3—3 of Fig. 1 looking in the direction of the arrows; and

Fig. 4 is a detail perspective of the spring ring between the plug and receptacle portions.

In order to give a general idea of our invention, it is here stated that the construction shown comprises a plug cluster having a plug portion 10, a receptacle portion 11, and a switch base 12, all of which are held in position with respect to each other by means of a long conducting screw 13, which forms a part of the electrical connection between the plug and the switch mechanism (not shown in detail).

The receptacle portion 11 carries the shell contacts 14 upon which are screwed the insulating bushings 15. The switch mechanism 15^a is carried by the switch base 12 upon which are also suitably mounted the center contacts 16. The switch mechanism comprises a switch for each receptacle and a plurality of pull chains 17 to operate each switch independently.

To give a more detailed description of our construction, the plug receptacle 10 has suitably supported thereon a threaded shell contact 18 which may be screwed into a suitable socket (not shown).

Integrally formed with the laterally extending threaded portion of the shell contact 18 is an inwardly extending flange portion 19, said flange portion having integrally formed therewith upwardly and downwardly extending fingers 20 and 21 respectively. The finger 20 extends upwardly into a recess 22 in the plug portion while the downwardly extending finger 21 extends into an arcuate recess 23 in the receptacle portion.

The recess 22 is slightly larger than the finger 20, said finger having no relative

movement therein. The recess 23, however in the receptacle portion in which the downwardly extending finger 21 extends, as shown in Fig 2, provides an arcuate path 5 of considerable extent in which the finger 21 may travel.

In use, when the plug portion is screwed into a suitable socket, the downwardly extending finger 21 will bear against the end 10 wall 24 of the recess 23 due to the fact that the receptacle portion is used as a handle for screwing the plug portion in.

After the plug portion is screwed in tight with the downwardly extending finger 21, 15 bearing against the end 25 of the recess 23, in order to adjust the receptacle to properly position either the electric light bulbs or pull chain, it is only necessary to turn the receptacle in the opposite direction to bring 20 the parts to the desired position, the lost motion connection between the plug portion 10 and the receptacle portion 11 permitting considerable rotative adjustment of the receptacle portion without any corresponding 25 rotative movement of the plug portion.

This construction enables a positive actuation of the plug portion by the receptacle portion both in screwing the plug in and in screwing it out and still permits relative 30 adjustment of the receptacle portion after the plug portion has been screwed completely in.

There is no adjusting or releasing means to manipulate in order to screw the plug 35 portion into its socket or to withdraw the plug portion from its socket although the receptacle portion is capable of being adjusted rotarily of its associate plug portion within the limit of the arcuate recess 40 23. In one instance, namely screwing the plug portion into its socket, the finger 21 may engage the end wall 24 of the recess 23 and in the other instance, namely withdrawing the plug portion from its socket, 45 the finger 21 may engage the end wall 25 of the recess. When the position of the receptacle portion is to be adjusted, it is free and unrestrained to be rotated in both directions within the confines of the arcuate 50 recess 23. As a consequence of our invention, the receptacle portion is capable of unrestrained relative adjustment relative to the plug portion in either direction through the limited arcuate span of the recess 23, 55 and the receptacle portion when turned in one direction serves as a handle for screwing the plug portion into its socket. After the plug portion has been screwed into its socket, the receptacle portion may then be 60 adjusted rotarily within the confines of the arcuate recess 23 in order to place the receptacle portion in the desired position. When the device is to be removed from the socket, the receptacle portion is unrestrained 65 in its movement until the finger 21 engages

the end wall 25 whereupon the plug portion can then be withdrawn from the socket.

The electrical connection between the plug shell contact 18 and the shell contacts 14 is obtained by provision of a spring friction 70 ring 26, (Fig. 4) which rests on the upper portion of the receptacle portion and has a finger 27 which extends downwardly into a recess 27^a in said receptacle portion. This ring has two additional shorter fingers 75 28 and 29 respectively which, as shown in Fig. 2, extend down into offset portions 30 and 31 of the recess 23, which positions said ring 26 firmly on the receptacle portion 11.

As shown in Fig. 4, the ring 26 is bent 80 upwardly at three points, these bent portions forming a sort of leaf spring between the plug portion and the receptacle portion 11 which will enable a good electrical connection to be obtained without binding of 85 the parts.

The downwardly extending finger 27 of the ring 26, as before mentioned, extends down into the recess 27^a in the receptacle portion. Bearing against this finger 27 is 90 a conducting member 32 having a hook portion 33 thereon which is sprung into the recess 27^a and bears against the wall 28^a thereof, thereby affording a positive and constant electrical connection between the 95 conducting member 32 and the downwardly extending finger 27. This member 32 extends downwardly and is supported upon the receptacle portion by the screw 34 whereby it is electrically connected at its 100 lower end with the arm 35 upon which is mounted the shell contact 14.

The circuit is from the center contact of the plug 10 through the screw 13, switch mechanism 15^a center contact 16 of the receptacle, through whatever translating device is inserted into the receptacle portion 11, through the threaded shell contact 14, thence through the arm 35, connecting member 32, finger 27 and ring 26 to the shell 110 contact 18 of plug 10.

The member 32, as herein shown, will allow for any inaccuracies in manufacture of the porcelain parts and will shift to compensate for these inaccuracies. However, this member 32 will at all times be in contact with the downwardly extending finger 27 of the ring 26, thus affording a constant electrical connection therebetween. 115

The conducting screw 13 which supports the receptacle portion 11 and the switch base 12 extends through an eyelet 36 in the switch base, this eyelet 36 serving to support a portion of the switch mechanism 120 15^a in place on the switch base.

The center contact member 16 held in place by the screw 37 is so formed and located on the switch base that when the electric light bulb engages said center contact, it will bear against and be supported 125 130

by the downwardly extending portion 38 of the switch base.

Having thus described our invention, what we claim as new and desire to secure 5 by Letters Patent is:

1. A plug receptacle comprising a plug portion having a threaded shell contact to be screwed into the corresponding threaded shell contact of a socket, a receptacle portion 10 electrically and mechanically connected with said plug portion, and means for mounting said portion with respect to each other whereby relative unrestrained rotation in either direction through a limited 15 arcuate span may be effected, said means allowing said receptacle portion when turned in one direction and at one extremity of said arcuate span to serve as a handle for screwing said plug portion into the 20 socket and when turned in the other direction and at the other extremity of said arcuate span to serve as a handle for unscrewing said plug portion from the socket, said receptacle portion after said plug portion 25 has been screwed into the socket then being capable of being turned freely in either direction within said limited arcuate span to bring said receptacle portion into desired position without unscrewing 30 the said plug portion from the socket.

2. A plug receptacle comprising a plug portion having a side contact for engagement with the side contact of a socket, said engagement to be effected by rotation of 35 the plug portion with respect to a socket, a receptacle portion mechanically and electrically connected with said plug portion, and means for mounting said plug portion and said receptacle portion with respect to 40 each other whereby relative unrestrained rotation in either direction through a limited arcuate span may be effected, said means allowing said receptacle portion when turned in one direction and at one extremity 45 of said arcuate span to serve as a hand hold for rotating said plug portion to connect it electrically with the socket and when turned in the other direction and at the other extremity of said arcuate span to 50 serve as a hand hold for unscrewing said plug portion from the socket, and said receptacle portion, after said plug portion has been screwed into the socket, then being capable of being turned freely in either 55 direction through said limited arcuate span

to adjust said receptacle portion in desired position without rotating said plug portion in said socket.

3. An electrical device comprising a plug portion and a second portion, said plug portion comprising an insulating base and a threaded shell contact, said base having a recess therein and said threaded shell contact having a lug struck-up therefrom and entering said recess to prevent relative rotation between said base and contact, means whereby said second portion is swivelled with respect to said plug portion, said second portion comprising an insulating base having a recess therein, said threaded shell 60 contact having a lug struck downwardly therefrom and entering said recess, said recess being large enough to permit a limited movement of said lug therein, whereby a lost motion relation is provided between said plug portion and said second portion, whereby said second portion may be used as a hand-hold member to screw said plug portion into a socket and whereby said second portion 65 may thereafter be rotated with respect to said plug portion to bring it into the desired adjusted position.

4. An electrical device comprising a plug portion and a second portion, said plug portion comprising an insulating base and 70 threaded shell contact, said base having a recess therein and said threaded shell contact having a lug struck-up therefrom and entering said recess to prevent relative rotation between said base and contact, means whereby said second portion is swiveled with respect to said plug portion, said second portion comprising an insulating base 75 having an elongated arcuate recess therein, said threaded shell contact having a lug struck downwardly therefrom and entering said arcuate recess whereby a lost motion relation is provided between said plug portion and said second portion, whereby said second portion may be used as a hand-hold member to screw said plug portion into a socket and whereby said second portion 80 may thereafter be rotated with respect to said plug portion to bring it into the desired adjusted position.

In witness whereof, we have hereunto subscribed our names.

WALTER D. STEELE.
REUBEN B. BENJAMIN.
